UNITED STATES PATENT OFFICE

LYMAN F. WHITNEY, OF BOSTON, MASSACHUSETTS, ASSIGNOR, BY MESNE ASSIGNMENTS, TO STATOR REFRIGERATION, INC., A CORPORATION OF DELAWARE

FLUID PUMPING

Application filed January 6, 1927. Serial No. 159,342.

This invention relates to means for pumping a fluid without the use of moving mechanical parts, and more particularly to an improved method of inducing fluid movement by aspiration with a propellant fluid. While pumping means of this character is more particularly intended for use in a refrigeration system of the general type disclosed in the copending application of East-
man A. Weaver, Serial No. 733,699, filed Au-
gust 23, 1924, and my copending applica-
tions, Serial Nos. 159,343, 159,344, 159,345 and
159,346, filed on even date herewith, this in-
vention is also applicable to a wide variety
of uses wherein pumping of a fluid by aspira-
tion is desirable. Further aspects of the in-
vention more particularly pertain to the use
of improved pumping means of this charac-
ter as applied to a refrigerating system of
the type disclosed in the aforesaid copend-
ing applications, which system in general
comprises a refrigerant circuit and a circuit
for propelling fluid, which have a portion in
common adjacent the outlet of the aspirator
nozzle, whereby pumping of the refrigerant
may take place.

Among the structural improvements in-
volved in the present type of apparatus is an
improved arrangement of aspirators and pro-
pellent coolers or condensers, whereby maxi-
mum pumping efficiency may be attained
from a given amount of propellant which has
been heated to a given temperature. Accord-
ing to present conclusions based upon experi-
ments and data upon refrigerating systems
of this type, it appears that the greatest ef-
ficiency may be attained from a system where-
in the propellant fluid has a comparatively
high density and high boiling point in com-
parison with the density and boiling point
of the refrigerant under similar pressure con-
ditions. For example, a propellant fluid hav-
ing the characteristics of mercury has been
found to be advantageous when used with a
refrigerant such as water or water in a saline
or caustic solution since the propellant may
be readily separated from the refrigerant;
and the system disclosed herein as illustrat-
ing the preferred form of the invention is

more particularly suited to fluids of this char-
acter.

Further objects and advantages of the in-
vention will be apparent to those skilled in
the art upon a reading of the subjoined de-
scription and claims in conjunction with the
accompanying drawings, in which

Fig. 1 is a schematic view of a refrigeration system involving the principles of this invention;

Fig. 2 is a detailed view partly in eleva-
tion and partly in section;

Fig. 3 is an end elevation of a portion of
the apparatus;

Fig. 4 is a detailed sectional view of one
liquid trap;

Fig. 5 is a plan view of a portion of the ap-
paratus;

Fig. 6 is a sectional view of the propellant
trap;

Fig. 7 is a central longitudinal cross-sec-
tion of one form of the aspirator for the sec-
ond stage of compression; and

Fig. 8 is a similar view of the aspirator as-
sembly for the first stage of compression.

Referring to the accompanying drawings
and more particularly to Fig. 1 thereof, the
invention is illustrated as applied to a refrig-
erating system, which comprises a cooler 1,
which may be situated in a household refrig-
erator or in any other region which it is
desired to cool. Cooler 1 is connected by a
vapor duct 2 with a mixing chamber 3 into
which aspirator nozzle 4 is adapted to emit
the propellant fluid. The propellant fluid
receives its energy from a vaporizer 5 which
may be heated by any suitable means, such
as the gas burner 6 provided with primary
air valve 101 and having a secondary air
valve 102 venting into the outer tube 103
which surrounds the tube 104 for the primary
mixture. The combustion chamber 107 with-
in the vaporizer is provided with the outlet
or exhaust funnel 9 for burned gases, smoke
and the like. An upstanding outlet pipe 10
is located outside of funnel 9 and is designed
to conduct propellant vapor from the boiler
to its branches 11 which are connected with
the downwardly inclined aspirator nozzles
4 and 33 respectively. Aspirator nozzle 4

may preferably be of the conventional flared form to permit the release of the propellant fluid from the high pressure chamber 12 to the mixing chamber 3 and permit the pressure thereof to be transformed into kinetic energy, thus imparting a high velocity to the propellant fluid as it enters the mixing chamber.

Referring particularly to Fig. 8 it may be seen that a condenser funnel 43 is in concentric alignment with the downwardly inclined nozzle 4, this duct in the illustrated embodiment of the invention being comparatively elongate and having a comparatively small cross-sectional size, and being designed to receive a mixture of the propellant and propelled vapors and to impart energy to the refrigerant fluid at the expense of the energy of the propellant fluid while concomitantly condensing the latter. If desired, a suitable drain 16 may be provided at the bottom of the mixing chamber 3 and extend downward to a liquid trap 17, being adapted to receive condensed propellant fluid and to contain a static liquid column thereof to provide a liquid head to balance the boiler pressure, while preventing clogging of chamber 3 by condensed propellant. Funnel or duct 43 may form a condenser for the propellant fluid, being surrounded by a suitable jacket 67 which may be connected with a cooling radiator 19 by the inlet and outlet 21 and 22, respectively. Preferably the jacket, radiator, and connecting pipes are partially filled with a volatile cooling agent, such as alcohol or water, which will at least have a depth sufficient to seal the mouth of inlet pipe 21. Heat conducted through the wall of duct 43 is absorbed by the volatile cooling fluid and causes the latter to evaporate and rise to the radiator 19 which may be provided with suitable cooling fins 24 to assist radiation of the heat. Funnel 43 is provided with a continuation 14 at the lowermost portion of which is located a suitable drain 35 for conducting condensed propellant to trap 17, the level of the propellant liquid in this pipe also forming a liquid column to balance boiler pressure.

Preferably duct 43 has a downward inclination as shown, and pipe 14, forming a continuation thereof, has an upward curve which is continued into a vertical portion 26, which again is bent to provide an upwardly inclined portion 27, which, through the downward extension 28, is adapted to emit vapor into the second stage mixing chamber 3. Preferably pipe 14 is provided with suitable cooling means of any desired form, such as plates 29.

Due to the difference between the boiling points of the refrigerant and the propellant fluids, condensation of practically all of the propellant which passes through aspirator 4 occurs in duct 43 or in the mixing chamber 3, and therefore very little propellant fluid is

carried upward through pipe sections 26 and 27, further condensation taking place in the latter pipes and resulting in drainage of the propellant back to duct 35. On the other hand, the temperature of the refrigerant, being well above its condensation point at the existing pressure and it having been somewhat compressed by the first stage of aspiration, is somewhat cooled as it passes through pipe 14 into mixing chamber 3. This cooling serves to make the vapor more dense and compact as it enters the second stage mixing chamber, and therefore the second stage nozzle has a smaller volume of refrigerant vapor to pump.

As previously indicated, a second aspirator 33 is adapted to receive propellant vapor from one of the branches 11 of the pipe 10 and is adapted to impart the second stage of compression to the refrigerant vapor. Pumping of the fluid through compression tube 13 as a result of the second stage of aspiration takes place in a manner similar to that previously described, each of the aspirators and compression ducts preferably being shaped and proportioned to give the best pumping efficiency in accordance with vapor conditions in the respective stages. In a manner similar to that previously described in regard to the first aspirator assembly, compression duct 13 may be provided with drains 16 and 35 as well as a cooling jacket 67 which has connections with a second radiator 19.

The downwardly inclined compression funnel 13 has an upwardly extending continuation 47, as disclosed in Fig. 3, which is adapted to emit the compressed vapor into a separating chamber 46 from whence the vapor passes through pipe 50 to a condenser 49. This condenser may be of any desirable form, but may conveniently comprise, as shown, a single pipe 50 having oppositely disposed open loops, the legs of which are inclined, whereby the condensed refrigerant will tend to flow down the same to separating chamber 46. As shown, pipe 50 is provided with radiating fins 51, but any conventional form of heat-absorbing means may be substituted for the same. The mixing chamber 46 has an outlet 71 which terminates in a liquid trap 52, Fig. 6, having a connection 53 with the cooler 1.

Preferably the liquid trap 52 may comprise an upwardly inclined chamber 54 with the end of pipe 71 projecting downwardly into the lower part thereof, and this liquid trap may contain any liquid, such as the propellant, e. g., mercury, and is adapted to balance differences in pressure in the condenser 49 and the cooler 1. When a suitable amount of condensed fluid has gathered in tube 71, the liquid in the other leg of the trap will be forced upwardly and outwardly sufficient to admit the passage of some of the liquid refrigerant in tube 71 about the lower end

of that tube, whereupon, due to its lighter weight, it will rise to the top of the liquid in the opposite tube, and thus pass into the cooler 1. Since a certain amount of residual propellant fluid may be carried by the refrigerant past the separating chamber 46 into the cooler 1, suitable means are provided to permit the drainage of the heavier liquid propellant back to the boiler 5, such means comprising a pipe 60 connected with the pipe 35 and adapted to hold a suitable static liquid column in a similar manner. Pipe 60 comprises a liquid trap 61, which has a connection 63 with the cooler 1. Liquid trap 61 may preferably be sealed by propellant fluid, such as mercury, and upon the filling of its upstanding connection 63 with additional mercury, it will force the overflow of some of the mercury through the trap into the tube 60. It is advantageous to provide the liquid trap 61 with two connections with the cooler (Fig. 4), the outmost 64 of these connections projecting upwardly into the cooler to permit the upward flow of refrigerant that may have been carried into the trap by the heavier propellant.

Pipe 35' may preferably project slightly into the intermediate part of an upwardly inclined leg of trap 17 (Fig. 2). This leg terminates in pipe 16 and is adapted to permit the upward movement of any of the refrigerant which may have been entrained in the heavier mercury.

In the operation of a system of this character it is to be understood that liquid refrigerant in the cooler 1 is evaporated due to the action of the first stage aspirator, which causes some compression of the vapor in the funnel 13, the propellant fluid being condensed out of the refrigerant vapor and the latter being cooled in pipe 14 as it passes to the second stage mixing chamber when, by the action of the second aspirator, it is further compressed and forced into condenser 49, where condensation occurs at a temperature which is lower than that at which the propellant vapor is condensed; the refrigerant then returns as a liquid through trap 53 to the cooler, thus completing the cycle. Use of two or more stages of aspiration with interstage cooling of the refrigerant thus permits a more efficient pumping action than practical with single stage aspiration, especially when the refrigerant must be considerably compressed.

A salient feature of the invention consists in that propellant vapor is condensed out from the mixture of propellant and propelled fluids as soon as it has given up the effective portion of its kinetic energy so that the spent molecules of propellant do not mitigate against efficient operation. This condensation should be effected closely following the outlet of the aspirator and preferably along the portion of the passageway where the kine-

tic energy of the propellant is being transferred to the other fluid. Thus in the illustrated embodiment this condensation takes place in the condenser funnels 43 and 13 immediately following the chambers 3, principally in the necks of the funnels preceding the flaring portion thereof.

The condensation of propellant in this same region also has the unique function of increasing the rate of diffusion of the propellant particles radially outwardly through the fluid to be propelled thus increasing the efficiency of aspiration by obtaining more intimate mixing of the two fluids with less tendency for the propellant stream to remain concentrated along the axis of the passageway and therefore with increased transference of kinetic energy from the propellant to the pumped fluid. This action is due to the removal by condensation of the propellant around the periphery of the passageway, those particles of propellant which diffuse outwardly to the periphery, having thereby given up most of their effective kinetic energy, condensing out so as not to impede the diffusion of succeeding particles.

While I have disclosed the use of multi-stage aspiration in conjunction with a refrigerating system, it is evident that the same principles affording similar increased efficiency of pumping may advantageously be used in other types of apparatus wherein aspiration of a propellant fluid is used to pump a second fluid; and in so far as the terms of the appended claims permit, I desire to include the use of this invention in all appropriate installations rather than confining the same to a refrigerating system of the type disclosed.

I claim:

1. The method of pumping fluid through a duct which comprises propelling the fluid at successive stages along the duct by aspiration with the vapor of a propellant liquid having a higher boiling point than the fluid, and after each of said stages removing the propellant liquid as its energy is exhausted, between said stages further cooling the pumped fluid to a temperature above its condensation point, and condensing the fluid after the last stage of aspiration.

2. Apparatus of the character described comprising a fluid duct including means for pumping fluid, said means comprising two aspirator nozzles with propellant condensers adjoining the outlets of each of the same, a cooler between one of the condensers and the succeeding aspirator, and a third condenser connected to the outlet of the condenser adjoining the outlet of the second aspirator nozzle.

3. Apparatus of the character described comprising a fluid duct including means for pumping fluid, said means comprising a plurality of aspirator nozzles with propellant

condensers adjoining the outlets of each of the same, another condenser connected to the outlet of the condenser adjoining one aspirator, each of the condensers adjoining the aspirator nozzles having a restricted size and cooling area to effect the condensation of a propellant fluid having a high condensation temperature without condensing a pumped fluid having a lower condensation temperature.

4. Apparatus of the character described comprising a fluid duct including means for pumping the fluid, said means comprising two aspirator nozzles with propellant condensers adjoining the outlets of each of the same, a condenser connected to the outlet of the condenser adjoining the second aspirator, each of said condensers adjoining said aspirators having a restricted cross-sectional passage in concentric alignment with the nozzles for effecting the simultaneous condensation of propellant fluid and compression of pumped fluid.

5. Apparatus of the character described comprising a fluid duct including means for pumping the fluid, said means comprising two aspirator nozzles with propellant condensers adjoining the outlets of each of the same, a cooler between one of the condensers and the succeeding aspirator and a third condenser connected to the outlet of the condenser adjoining the second aspirator, each of said condensers adjoining said aspirator nozzle having a restricted size and cooling area to effect condensation of a propellant fluid having a high condensation temperature without condensing a pumped fluid having a lower condensation pressure, said third condenser having a comparatively large heat distributing area to effect condensation of pumped fluid at a low temperature.

6. The art of pumping a condensable vapor with a condensable vapor having a higher condensation point which comprises impelling the first vapor by direct action thereon by the second vapor at successive locations, condensing out substantially all the second vapor entering the cycle at the first location intermediate the two locations, condensing out substantially all the second vapor entering the cycle at the second location at a location following the second location, and at a subsequent location condensing the first vapor at a lower temperature.

7. Apparatus of the class described comprising means for entraining a pumped fluid in a stream of propellant vapor, including a mixing chamber having a fluid inlet, a propellant nozzle discharging into the mixing chamber at one side, a duct leading from the other side of the mixing chamber in alignment with said nozzle and having a portion of comparatively small cross-sectional area, and means to condense spent propellant vapor in said duct, the length of the small

portion of said duct being at least approximately twice as great as the distance between the nozzle outlet and the duct inlet.

8. Apparatus of the class described comprising a propellant nozzle, a mixing chamber at the outlet of said nozzle, a compression duct aligned with said nozzle, said duct having an elongate portion gradually decreasing in size whereby the duct has its portion of smallest diameter considerably spaced from the nozzle, said last-named portion having a diameter near that of the outlet of the nozzle, and said duct having an outwardly flared portion beyond the portion of smallest diameter.

Signed by me at Boston, Massachusetts, this 20th day of December, 1926.
